UNITED STATES PATENT OFFICE.

FREDERICK RAPP, OF CHICAGO, ILLINOIS.

DESIGN FOR A WATCH-CASE.

SPECIFICATION forming part of Design No. 17,284, dated April 26, 1887.

Application filed June 21, 1886. Serial No. 205,833. Term of patent 7 years.

To all whom it may concern:

Be it known that I, FREDERICK RAPP, a citizen of the United States, residing at Chicago, in the county of Cook and State of Illinois, have invented a certain new and original Design for Watch-Cases, which is fully set forth in the following specification, reference being had to the accompanying drawings, forming a part hereof, and in which—

10 Figure 1 is a side view of my newly-designed watch-case, showing the same closed; and Fig. 2 shows the same view with the cover of the case open.

15 Fig. 1 shows in side view a watch-case in the form of a fish having spines upon its back and belly, the tail of the fish forming the stem

of the watch. The lid on the side of the watch covers a circular opening, beneath and in which is the face of the watch. The body of the fish is longitudinally short, vertically deep, 20 and laterally thin.

What I claim is—

The design for a watch-case herein shown and described, the same being in the form of a fish with longitudinally short, vertically 25 deep, and laterally thin body, having upon one of the sides the circular opening, as set forth.

FREDERICK RAPP.
